UNITED STATES PATENT OFFICE.

JOHN VOLLMER, OF ESSEN, GERMANY, ASSIGNOR TO FRIED. KRUPP AKTIEN-
GESELLSCHAFT, OF ESSEN-ON-THE-RUHR, GERMANY.

GUN-BARREL BUILT OF AN A-TUBE AND A BREECH-PIECE.

1,398,819.

Specification of Letters Patent.

Patented Nov. 29, 1921.

Application filed December 3, 1920. Serial No. 428,086.

To all whom it may concern:

Be it known that I, JOHN VOLLMER, residing at Essen, Germany, a citizen of the German Republic, have invented a certain new and useful Improvement in a Gun-Barrel Built of an A-tube and a Breech-Piece, (for which I have filed application in Germany, May 31, 1917,) of which the following is a specification.

10 This invention relates to gun-barrels built of an A-tube and a breech-piece, the latter being formed with a jacket portion which envelops the A-tube. The object of the invention is to provide such a connection between the said two parts of the gun-barrel as will combine sufficient resistance to the stresses set up on firing with as low a weight as possible of the connecting parts, while effectually sealing the joint between the component parts of the gun-barrel.

15 Referring to the annexed drawing:—

Figure 1 is a longitudinal section of the parts in question of a constructional example of the invention;

20 Fig. 2 is a section at 2—2 in Fig. 1, seen from the right;

Fig. 3 is a longitudinal section of a second constructional example of the invention;

25 Fig. 4 is a section at 4—4 in Fig. 3, seen from the right.

The gun-barrel shown in Figs. 1 and 2, which will be described first, consists of a double A-tube A A¹ (Fig. 1) and a breech-piece B, the latter being formed with a jacket portion b¹ which envelops the rear portion of the A-tube. The connection between the breech-piece and the A-tube is obtained by screwing the former on the latter. For this purpose, the outer layer A¹ of the 30 A-tube is provided with a screw thread a², and the jacket portion b¹ of the breech-piece is provided with corresponding female thread b². b³ denotes the slot to take the breech block, and b⁴ the loading aperture 35 in the breech-piece B. The cylindrical wall b⁷ (Fig. 1) of the bore of the jacket portion b¹ destined to receive the A-tube is sloped off into the rear face b⁵ of the said bore by an arc b⁶ struck with a comparatively long 40 radius, the said slope commencing at a point situated in rear of the end face at a³ of the inner layer A of the A-tube. This end face a³ lies in one plane with the end face a⁴ of the outer layer A¹ of the A-tube. Between

the faces a³, a⁴ and b⁵ there remain two dish-shaped empty spaces which open into the breech slot b³. These spaces are filled up by means of two segment-shaped packing pieces C which are attached to the breech-piece B by fixing screws D.

Owing to the fact that the wall b⁷ of the jacket portion b¹, instead of making a sharp or a slightly rounded angle with the face b⁵ is sloped off into the latter with an arc struck with a long radius, and that the A-tube 65 retains its full diameter right up its rear faces a³ a⁴, great resistance of the breech-piece to cracking at the dangerous section where the wall b⁷ merges into the face b⁵, and sufficient strength of the A-tube up to 70 its rear end to prevent expansion under the pressure of the powder gases, are obtained, together with the least weight possible of the parts in question. The packing pieces C prevent dust and dirt penetrating into 75 the joint between the layers A A¹ of the A-tube and into the screw joint a² b² between the A-tube and the jacket portion b¹ of the breech-piece. They also afford protection 80 against formation of rust at the said joints and prevent the inner layer A, the so-called liner of the A-tube from setting back into 85 the breech slot b³ and thus from jamming the breech-block.

The second constructional example differs 85 from the first only in that the packing pieces C fixed to the breech-piece B are dispensed with, the rear end of the outer layer A¹ of the A-tube A A¹ being provided, instead, with extensions a⁵ of suitable shape. In order that a certain amount of clearance may be provided for the screwing the breech-piece on the A-tube and placing their connection under tension, the length of the extensions a⁵ is determined in such a manner 90 that they do not reach quite up to the face b⁵ (Fig. 3) of the breech-piece when the breech-piece assumes its correct position relative to the A-tube. The intervals E are closed, towards the breech slot b³, by covering strips F running parallel to the front face of the breech slot. The said strips, which bear against the rear face a³ of the liner A, engage undercut grooves b⁸ (Fig. 3) of the breech-piece, so that they cannot 95 protrude into the breech slot. Endwise motion of the strips F is prevented by fixing screws G. The strips F prevent the en-

trance of dirt into the intervals E and effectually prevent the liner A from setting back into the breech slot b³.

In gun-barrels of the construction shown in Figs. 1 and 2, similar strips can be employed, in case it should be considered desirable to leave narrow gaps between the end faces a³ a⁴ of the A-tube and the packing pieces C. The height of the latter would then have to be reduced by an amount equal to the thickness of the strips.

Claims:

1. A composite gun barrel comprising a breech-piece provided with a bore and an A-tube adapted for screw threaded engagement therewith, the bore of said breech-piece terminating in an arc-shaped face curved on a large radius, and packing pieces disposed in the arc-shaped face of said bore 20 and adjacent the end of the A-tube.
2. A composite gun barrel comprising an A-tube and a breech-piece, said breech-piece being formed with a bore and provided with screw threads for receiving the end of the 25 A-tube, the rear face of said bore being arc-shaped with an arc struck on a large radius, said arc shaped face commencing at a point to the rear of the adjacent end of the A-tube, and packing pieces disposed between the arc-shaped face and the end of the A-tube.
3. A composite gun barrel comprising a

breech-piece and an A-tube comprising an outer member and a liner, said breech-piece being provided with a bore for the reception of the A-tube, the cylindrical wall of said bore being sloped off into the rear face of the said bore by an arc struck with a large radius, the said slope commencing at a point in the rear of the end face of the liner of the A-tube, and packing-pieces in 40 the rear portion of the bore of the breech-piece.

4. A composite gun barrel comprising a breech-piece and an A-tube comprising an outer member and a liner, said breech-piece 45 being provided with a bore for the reception of the A-tube, the cylindrical wall of said bore being sloped off into the rear face of the said bore by an arc struck with a large radius, the said slope commencing at 50 a point in the rear of the end face of the liner of the A-tube and packing-pieces disposed between the rear face of the bore of the breech-piece and the end face of the A-tube.

The foregoing specification signed at Es-
sen, Germany, this 24th day of June, 1920.

JOHN VOLLMER.

In presence of—

HANS GOTTMANN,
JOHANN DECKERS.
